UNITED STATES PATENT OFFICE.

JOHN R. HALLEY, OF NASHVILLE, IOWA.

CHURN.

SPECIFICATION forming part of Letters Patent No. 599,332, dated February 22, 1898.

Application filed January 4, 1897. Serial No. 617,883. (No model.)

To all whom it may concern:

Be it known that I, JOHN R. HALLEY, of Nashville, Jackson county, Iowa, have invented certain Improvements in Churn-Paddles, of which the following is a specification.

My invention relates to improvements in that class of churns in which the churn-body and the paddle or agitator revolve in opposite directions; and it consists more particularly in an improved form of fastening for the paddle-shaft.

My invention further consists in the specific features of construction hereinafter particularly described and claimed.

15 In the accompanying drawings, forming part of this specification, Figure 1 is a perspective view of a churn embodying my invention, partially broken away to show the interior construction. Fig. 2 is a partial vertical cross-section of the barrel and the contained paddle. Fig. 3 is a detail view of the bearing-block for one end of the paddle-shaft, and Figs. 4 and 5 are details of my improved fastening for the opposite end of the paddle-shaft.

20 In the drawings, A represents the churn-frame, of any suitable construction, and, as shown, comprising the base 2 and parallel upright standards 3.

25 B is the churn body or barrel, having journal support in the frame A by means of the gudgeons 4, turning in the tops of the standards 3, one of the gudgeons being provided with a handle 5, by means of which the churn may be rotated.

30 C is the agitator or paddle, arranged within the churn, as shown in Fig. 1. The paddle is formed with radiating wings 6, centrally cutaway, as shown. The paddles are secured 35 in the churn by means of the fastenings illustrated in Figs. 3 to 5. A block 7 is secured to the inner side of the churn-body by means of screws 8 and is formed with a central opening 9, serving as a bearing for one end of the 40 paddle-shaft. To the opposite side wall of the churn is secured a similar block 10, provided with my improved form of fastening. This consists of a spring D, arranged in a groove 11 in the top of the block and secured 45 thereto by means of screws 12, passing through the eyes 13. The spring is shaped so as to 50 form a bearing portion 14 and a stirrup por-

tion 15 at the top, with an intermediate contracted neck 16. Thus in placing the paddles in the churn one end of the paddle-shaft 55 is placed in the opening 9 in the block 7, with the opposite end resting in the stirrup 15 of the spring D. By then pressing the paddle down the spring will be forced open, allowing the end of the shaft to pass below the neck 60 16, as shown in Fig. 4. The top of the block is formed with a circular socket 17, in which the rod will rest when in place. The paddle may be easily removed by lifting upon the end next the spring-fastening with sufficient 65 force to open the spring.

As will be seen, in my improved form of fastening there are no parts to get out of order and the paddle is much more easily inserted and removed than with the form of 70 fastening where there are any parts to be moved.

While I have shown my invention applied to a barrel churn, it will be evident that the same idea may be embodied in a revolving-box churn. In both constructions of churn the paddles are centrally cut away, as shown. With a solid paddle the milk striking against the center would be likely to throw the paddle out of its fastenings. 75

I claim—

1. In a churn, the combination with its rotary paddle, of the bearing-block adapted to receive one journal of the paddle-shaft, the open-top bearing-block for the other journal, 85 and the two-part spring-clasp for holding said journal upon said block, the members of said clasp being brought toward each other above said journal, and then spread apart in V-shaped position, whereby the journal may be 90 inserted by merely pressing the same down between said members, or removed from said block by lifting it upward.

2. In a churn, the combination with the rotary paddle and its shaft, of the bearing-block 95 adapted to receive one journal of the paddle-shaft, the open-top bearing-block for the other journal, and the spring secured in said block, and serving as a bearing for the end of the paddle-shaft, and constructed above said 100 shaft to hold the same in place, but adapted to be opened to release the shaft by means of pressure exerted against the paddle.

3. In a churn of the class described, the

combination with the rotary paddle and its shaft, of a suitable bearing for one end of the shaft, the bearing-block for the other end, and the spring-clasp for receiving the shaft, 5 in the latter bearing, being so constructed as to hold the shaft in place and prevent movement of the same, and permit the shaft to be carried into or out of position by lateral

pressure exerted against the tension of the spring.

In testimony whereof I affix my signature in presence of two witnesses.

JOHN R. HALLEY.
